(57) **CLAIM**

We claim the ornamental design for a cover for electronic device, as shown and described.

DESCRIPTION

FIG. 1 is a front perspective view of a cover for electronic device showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is an enlarged view of the encircled portion in FIG. 4;

FIG. 10 is an enlarged view of the encircled portion in FIG. 6;

FIG. 11 is an enlarged view of the encircled portion in FIG. 7; and,

FIG. 12 is a front perspective view thereof in an example environment of use.

The broken lines in the figures depict portions of the cover for electronic device that form no part of the claimed design. The broken lines in FIG. 12 depicting the example environment of use form no part of the claimed design. The dot-dot-dash broken lines encircling enlarged portions of the claimed design form no part thereof.
